(57) **CLAIM**

I claim the ornamental design for a floor lamp, as shown and described.

DESCRIPTION

FIG. 1 is a top perspective view of a floor lamp of the present design.

FIG. 2 is a bottom perspective view of the floor lamp of FIG. 1.

FIG. 3 is a front elevation view of the floor lamp of FIG. 1.

FIG. 4 is a rear elevation view of the floor lamp of FIG. 1.

FIG. 5 is a left side elevation view of the floor lamp of FIG. 1.

FIG. 6 is a right side elevation view of the floor lamp of FIG. 1.

FIG. 7 is a top plan view of the floor lamp of FIG. 1.

FIG. 8 is a bottom plan view of the floor lamp of FIG. 1.

FIG. 9 is a top perspective view of the floor lamp of the present design.

FIG. 10 is a bottom perspective view of the floor lamp of FIG. 9.

FIG. 11 is a front elevation view of the floor lamp of FIG. 9.

FIG. 12 is a rear elevation view of the floor lamp of FIG. 9.

FIG. 13 is a left side elevation view of the floor lamp of FIG. 9.

FIG. 14 is a right side elevation view of the floor lamp of FIG. 9.

FIG. 15 is a top plan view of the floor lamp of FIG. 9; and, FIG. 16 is a bottom plan view of the floor lamp of FIG. 9. The broken line disclosure of the shade represents a portion of the lamp which forms no part of the claimed design.
